Attorney

UNITED STATES PATENT OFFICE.

CHARLES A. DARIUS, OF MONTCLAIR, NEW JERSEY.

PREHEATER.

Application filed May 4, 1922, Serial No. 558,478. Renewed November 8, 1924.

To all whom it may concern:

Be it known that I, CHARLES A. DARIUS, a citizen of the United States of America, residing at Montclair, in the county of 5 Essex and State of New Jersey, have invented certain new and useful Improvements in Preheaters, of which the following is a specification.

This invention relates to certain new and useful improvements in pre-heaters intended to be secured in operative position within furnaces or boilers, and which are preferably mounted upon the feed door to swing therewith, the type of pre-heaters to which the invention relates being of that kind involving a baffling means adapted to cause air entering the furnace above the fire to follow a tortuous path and thus become efficiently pre-heated.

20 The primary object of the present invention is to generally simplify and improve devices of this character so that the construction will lend itself to existing manufacturing conditions for production in large 25 quantities at a minimum cost and for producing a pre-heater of simple construction as well as of durable form.

With the above general objects in view and others that will appear as the nature 30 of the invention is better understood, the same consists of the novel form, combination and arrangement of parts hereinafter more fully described, shown in the accompanying drawings and claims.

35 In the drawings, wherein like reference characters designate corresponding parts throughout the several views,

Figure 1 is a fragmentary front elevational view of a furnace with its air feeding door having a pre-heater attached thereto constructed in accordance with the present invention, the pre-heater being indicated in outline by dotted lines,

40 Figure 2 is a vertical section on the line II—II of Figure 1,

Figure 3 is a vertical sectional view of a modified form of pre-heater constructed in accordance with the present invention,

45 Figure 4 is a rear elevational view of the device shown attached to the door of the furnace in Figure 2,

Figure 5 is a side elevational view of one of the inner pans of the pre-heater,

Figure 6 is an elevational view of the device shown in Figure 5, looking toward 55 the right of the latter figure, and,

Figure 7 is an enlarged view of the device shown in Figure 5 and drawn in vertical section.

Referring in detail to the several views, 60 the furnace wall 5 has a door 6 hinged thereto as at 7 along one side of an opening provided in said wall and this door is provided with the usual slots for admitting air into the combustion chamber of the furnace, the amount of air being controlled by 65 a sliding damper 8 or the like.

The present invention is adapted to be attached to the inner surface of the door 6 and aligned with the openings of said door 70 so as to project inwardly of the furnace, and in the form shown in Figures 1 and 2, the device embodies a pair of metal pans 75 9 and 10 which are nested in reverse position and which are preferably constructed of sheet metal similar to the structure of ordinary bake pans wherein all of the side walls of each pan converge in the same direction. As is well known, these pans are open at the top and provided with a bottom wall and the outer pan 9 may be suspended by means of suitable hooks 11 attached to the upper wall thereof and engaged in suitable eye members 12 fixed to the upper part of the door 6, the pans then 80 85 swinging and remaining in contact with the inner face of the door through gravity and being readily detachable but obviously any other manner of mounting the pans 9 and 10 upon the door 6 may be employed. In accordance with the present invention, the inner pan 10 is perforated as at 13 in one or more of its side walls while the bottom wall of the same is imperforate and preferably concaved inwardly so that the air may 90 pass readily to the space between the sides of the two pans. The sides of the outer pan 9 are imperforate and the bottom wall thereof is perforated as at 14, the preferred construction being the provision of relatively larger and a smaller number of perforations or openings in the pan 10 than in

the pan 9, thus effecting a more thorough baffling of the air before it passes out of the perforations 14 to the combustion chamber. It will be noted that the perforations 14 in the pan 9 are relatively small in size and largely increased in number with respect to the openings 13 in the pan 10, and substantially extend over the entire bottom wall of the pan 9. By the provision of 10 a large number of very small perforations in the pan 9 so located as the inlet for the preheated air, a multiplicity of very fine jets of air are fed into the combustion chamber above the fire for mixture with the gases 15 therein, increasing combustion and insuring the maximum consumption of the fuel. The fine jets of air thoroughly comingle with the combustible furnace gases and are drawn through the preheater, any blowing 20 action thereof from a point exteriorly of the feed door being prevented by an effective baffle of the air caused by the reduction of size of the perforations in the direction of travel of the air as well as the tortuous path thereof. The preheated air supply is thus very finely subdivided on the similar principle as is involved in the air-feed of an internal combustion engine, where the air is substantially atomized.

Obviously, the bottom of the inner pan 10 may also be perforated if found desirable as indicated at 13' with respect to the modified form of this pan shown at 10' in Figure 7. Otherwise the construction of the 25 pan in Figure 7 is the same as in Figure 2.

As shown in Figure 3, the device may be indefinitely extended inwardly by the additional association of nested pans, although there should not be such number of pans 40 associated as will not swing clear of the furnace door opening when said door is opened. In Figure 3 another unit is added comprising reversely disposed and nested pans 9^a and 10^a respectively, similar to the pans 9 and 45 10 and with the pan 9^a tightly fitting over the bottom of the pan 9 and frictionally retained in place or otherwise as found desirable. The pans 9^a and 10^a are otherwise of the same construction as the pans 9 and 50 10 except that the same are made smaller with the pan 10 of shallower form than the pan 9^a so that the pans 9 and 9^a may be nested to a slight extent before the bottom of the pan 10^a contacts with the bottom of 55 the pan 9.

In operation the desired amount of air will be allowed to flow through the openings or slots by regulation of the damper plate 8 and this air will pass to the space between the side walls of the pans 9 and 10 or a part of the same will pass through the perforations in the bottom of the pan 10' when the latter is employed. The air will pass through the perforations in the side of 60 65 the pan 10 to the interior of the latter and

then outwardly through the perforations 14 of the pan 9. Due to the tortuous path of travel of the air and the difference in size and number of the perforations provided in the two pans, a very efficient baffling action is 70 had whereby the heat of the walls of the pan members will be radiated to the air and the latter effectively pre-heated before discharge into the combustion chamber of the furnace. As shown in Figure 4, the openings 14, in the bottom wall of the outer pan 9, are also smaller in area than the intervening unperforated spaces between them, thereby affording effectual means for still further raising the temperature of the 75 already preheated air, before and as it is drawn into the combustion chamber, by intimate contact with the hot metal of the bottom of the outer pan, to a degree more nearly approximating that obtaining within 80 the combustion chamber itself.

From the foregoing description, it is believed that the construction and operation, as well as the manner of use of the present device will be readily apparent and it will 85 be seen that the invention provides a simple and efficient construction capable of being manufactured at a low cost in large quantities and readily installed for use.

Having thus described the invention, what I claim as new is:—

1. An air pre-heater attachment for furnace doors embodying reversely disposed and nested metal pan members perforated to provide a tortuous path of air from the open end of the outer pan through the bottom of the latter and through walls of the inner pan, and means to attach the device to a furnace door with the open end of the outer pan contiguous with the inner surface of said door.

2. An air pre-heater attachment for furnace doors embodying reversely disposed and nested metal pan members perforated to provide a circuitous path of air from the open end of the outer pan through the bottom of the latter and through walls of the inner pan, and means to attach the device to a furnace door with the open end of the outer pan contiguous with the inner surface of said door, said pans having side walls all converged in the same direction with relation to their open ends.

3. An air pre-heater attachment for furnace doors embodying reversely disposed and nested metal pan members perforated to provide a circuitous path of air from the open end of the outer pan through the bottom of the latter and through walls of the inner pan, and means to attach the device to a furnace door with the open end of the outer pan contiguous with the inner surface of said door, said pans having side walls all converged in the same direction with relation to their open ends, and the inner wall 120

- or bottom wall of the inner pan being inwardly concaved.
4. An air pre-heater attachment for furnace doors embodying reversely disposed and nested metal pan members perforated to provide a tortuous path of air from the open end of the outer pan through the bottom of the latter and through walls of the inner pan, and means to attach the device to a furnace door with the open end of the outer pan contiguous with the inner surface of said door, the inner pan having perforations in the side walls thereof and the outer pan having imperforate side walls and perforations in the bottom wall thereof, the first named perforations being larger and fewer in number than the latter perforations.
5. An air pre-heater attachment for furnace doors embodying reversely disposed and nested sheet metal pan members perforated to provide a circuitous path of air from the open end of the outer pan through the bottom of the latter and through walls of the inner pan, and means to removably attach the device to a furnace door with the open end of the outer pan contiguous with the inner surface of said door.
6. An air pre-heater for furnace doors comprising a plurality of baffling units each embodying reversely disposed nested pans with the walls of each pan all converging in the same direction and with the walls of the inner pan sloping in the different direction to the walls of the outer pan, said walls of the inner pan being perforated and said walls of the outer pan being imperforate with the bottom wall of the outer pan perforated, and means to attach the outer pan of the unit nearest the furnace door to the latter, said outer pan of the first unit having the outer pan of the next unit telescoped onto the same.
7. An air pre-heater attachment for furnace doors comprising air-baffling members consisting of reversely disposed nested pans with the walls of the inner pan sloping in a different direction from the slope of the walls of the outer pan so as to form an air space between the inner and outer walls, said walls of the inner pan being perforated and said walls of the outer pan being imperforate with the bottom of the outer pan perforated.
8. An air pre-heater attachment for furnace doors comprising air-baffling members consisting of reversely disposed nested pans with the walls of the inner pan sloping in a different direction from the slope of the walls of the outer pan so as to form an air space between the inner and outer walls, said walls of the inner pan being perforated and said walls of the outer pan being imperforate with the bottom of the outer pan perforated, and with the said perforations in the walls of the inner pan larger and fewer in number than those in the bottom of the outer pan.
9. An air preheater for furnaces and boilers comprising a plurality of baffling members consisting of reversely disposed nested pans, with the walls of the inner pan sloping in a different direction to the walls of the outer pan, said walls of the inner pan being perforated and said walls of the outer pan being imperforate, and with bottom wall of the outer pan perforated.
10. An air preheater for a furnace or boiler consisting of reversely nested inner and outer pans, so perforated and disposed as to permit the passage of air from without the furnace, into and between the walls of the inner and outer pans, into the inner pan, through perforations of the inner pan, and thence into the combustion chamber through perforations in the bottom of the outer pan.
11. An air preheater for a furnace or boiler consisting of reversely nested inner and outer pans, so perforated and disposed as to permit the passage of air from without the furnace, into and between the walls of the inner and outer pans, into the inner pan, through perforations of the inner pan, thence into the combustion chamber through perforations in the bottom of the outer pan, with the perforations so disposed that the same will be larger and relatively fewer in number at the near end and smaller and relatively greater in number toward the far end.
12. An air preheater for furnaces or boilers consisting of reversely nested perforated baffling pans, with the open end of the inner pan contiguous with the bottom wall of the outer pan, and having their side walls assuming a different direction so as to form wedge-shaped air-spacing between related side walls of the inner and outer pans.
13. An air preheater consisting of reversely nested perforated pans, the perforations being of different sizes and differing in number in successive baffling parts thereof.
14. An air preheater for furnaces comprising a plurality of reversely disposed nested pans, with the side walls of the pans sloping in opposite directions, and said pans being perforated in a manner to cause air in passing therethrough to be baffled and preheated, and issue in a multiplicity of very fine spray jets over the fire to mingle with the furnace gases within the combustion chamber.
15. An air preheater for furnaces comprising reversely nested pans, said pans being perforated in a manner to cause air in passing therethrough to be baffled and preheated, and issue in a multiplicity of very fine spray jets over the fire to mingle with

the furnace gases within the combustion chamber.

16. An air-preheater of the kind described comprising reversely nested pans, with the side walls of the pans thus nested having a different direction so as to form an angular air space between them, the side walls of the inner space being perfor-

rated and the bottom wall of the outer pan being perforated with its sides imperforate, ¹⁰ with the area of the openings in said bottom wall substantially less than the area of the intervening spaces.

In testimony whereof I affix my signature.

CHARLES A. DARIUS.
